DUST MOP OR OIL MOP CLEANER

Jean H. Marshall, Chicago, Ill., assignor of
one-half to Robert W. Muir, Barrington, Ill.

Application May 22, 1929. Serial No. 365,058

2 Claims. (Cl. 15—142)

This invention relates to cleaners for dust mops, also sometimes known as floor mops, and also as oil mops.

Objects of this invention are to provide a cleaner which will efficiently clean the dust or oil mop; which is light enough to be easily carried from room to room; which permits the cleaning of the mop in the room where it is being used; which retains the dust during the cleaning operation, and at all times; which eliminates the clogging of the cleaning surfaces by hair, string, and other foreign substances; and which is provided with a removable cleaning element to permit the ready disposal of the accumulated dust.

Further objects of my invention are to provide a dust mop cleaner that will serve as a receptacle in which to keep the mop when not in use; to provide a cleaner with a handle or bail that engages the handle of the mop and holds it upright when not in use; to provide a cleaner with a handle or bail that engages the handle of the mop and prevents it from slipping to either side when not in use; a cleaner the handle or bail of which is so constructed that the operator's foot may be pressed on it to hold the cleaner firmly positioned while the dust is being removed from the mop.

Further objects are to provide a cleaner for dust or oil mops that can be inexpensively constructed; that will occupy but little space; that has no moving parts; and that will not present an unsightly appearance at any time.

I accomplish the above objects and others which will become apparent as the description proceeds and when taken in connection with the accompanying drawing, as illustrative of my invention, reference is had to:

Figure 1, which is an elevation of the cleaner for dust or oil mops embodying my invention, showing the mop in the cleaner in position for cleaning, a part of the receptacle being broken away to show the interior construction.

Figure 2 is a plan view of the cleaner.

Figure 3 is an enlarged sectional view of the cleaning element.

Figure 4 is an enlarged vertical cross-section of the ear which holds the bail or handle of the receptacle firmly attached thereto.

The receptacle 1 may be an ordinary pail such as is used for general household purposes, preferably provided with a fluted sidewall 2, and with a special bail or handle 3 which is provided in its central portion with an open loop 4 and is attached to the pail by ears 5.

The cleaning element 6 comprises a plurality of curved blades 7 radiating from a higher central portion or crown which may be provided with a cover 8 over the central portion of the cleaning element 6. The blades 7 curve downward from the crown for a short distance and then turn upward to form an overhanging portion 10. The blades then curve downward on the outer portion of the cleaning element 6 to form a straight portion 11 so constructed that it contacts along its length with the middle portion of the sidewall 2 of receptacle 1.

The ears 5 may be spot-welded to receptacle 1, or may be attached thereto by means of rivets 12, and are provided with a notch 13 and with 70 an elongated opening 14 into which the ends 15 of bail or handle 3 are fastened by a closed loop.

In the operation of the cleaner the cleaning element 6 is placed in the receptacle 1 and 75 pressed down until the outer portions 11 press firmly against the inside of sidewall 2, thus binding the cleaning element 6 and preventing it from turning, or dropping deeper into receptacle 1. The dust mop or oil mop (shown in outline in Figure 1 in position for cleaning) is then inserted into receptacle 1 until it rests on cleaning element 6. The mop is then rotated backward and forward and the dust is scraped off the strands of the mop by the 80 blades 7, the upturned portions 10 assisting in the removal of the dust. The dust is not removed by beating the mop against the blades 7, but by the drawing of the strands of the mop across the blades 7. A few backward and forward rotations will suffice for the removal of the accumulated dust, and permit the mop to be used to continue the cleaning.

While rotating the mop backward and forward in the cleaner the foot of the operator is 95 placed on open loop 4 of bail or handle 3, which has been turned down so it rests near the floor. The pressure of the foot holds the cleaner firmly positioned while the cleaning process is going on. Should an interruption occur during the time 100 the mop and cleaner are in use the bail or handle 3 is raised to an upright position and ends 15 engage in notch 13. The handle of the mop is then placed in open loop 4 thus providing a resting place for the mop by which it is held 105 upright in the cleaner until the use of the mop is resumed. This same procedure can be followed when the dusting has been completed and the mop and cleaner have been set away till again needed, or the mop handle can be placed 110

in open loop 4 in other than a vertical position, so the mop cannot slip to either side.

When the cleaner has been in use for some time—possibly a month—the accumulated dust 5 and other foreign matter can be emptied out of the cleaner either by shaking thru the blades 7, or—and preferably—by pulling cleaning element 6 out of receptacle 1 and emptying the receptacle, after which the cleaning element is 10 replaced.

In the process of cleaning, the mop flattens out over the blades 7 forming a cover which prevents any escape of dust into the room. There are no eddying currents within the receptacle 1 during the cleaning operation, because the mop is rotated backward and forward, and is not pounded up and down. For these reasons no 15 dust escapes from the cleaner. The cover 8 is provided to serve as an additional scraper for the strands of the mop, and also serves to prevent the strands from approaching the center of the cleaning element 6, where a wedging effect might occur if cover 8 were not used.

While I have illustrated and described my in- 25

vention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

1. A device of the class described comprising a receptacle, a plurality of radially disposed curved blades removably set within the receptacle, and a cover cap over the central portion of the blades for the purpose above set forth. 80

2. A device of the class described comprising a receptacle, a plurality of radially disposed blades removably set within the receptacle, each blade curving downward from the center and curving upward toward its outer extremity into an overhanging tip for the purpose above set forth. 90
